APPARATUS FOR COILING STRIP METAL

Frank Marquart and William H. Stivason, Cleveland, Ohio, assignors to The American Steel & Wire Company of New Jersey, a corporation of New Jersey

Application December 17, 1940, Serial No. 370,560

6 Claims. (Cl. 242—78)

This invention relates to the coiling of continuous strip metal, and particularly to apparatus or means for determining the time required for coiling the same.

It is the general object of the present invention to provide an improved apparatus or means whereby the time that it is required to coil strip metal on a take-up block after it has been rolled or otherwise processed can be quickly and conveniently ascertained.

It is another object of this invention to provide an improved apparatus or means of determining the time for coiling continuous strip metal which is not only simple and inexpensive in its construction and use, but an apparatus which can be easily incorporated with existing equipment at a minimum expense.

It is a further object of the invention to provide an improved electrically controlled apparatus or means for determining the time for coiling continuous strip metal which is controlled by the strip itself and is substantially fool-proof, and yet an apparatus which accurately records the coiling time.

Various other objects and advantages of this invention will be more apparent in the course of the following specification and will be particularly pointed out in the appended claims.

In the accompanying drawing, there is shown for the purpose of illustration, one embodiment which our invention may assume in practice.

In the drawing:

Figure 1 is a plan view of rolling mill and coiling device showing the improved timing apparatus of our invention incorporated therewith;

Figure 2 is a side elevation of Figure 1;

Figure 3 is an enlarged section taken on the line III—III of Figure 1;

Figure 4 is a section taken on the line IV—IV of Figure 3; and

Figure 5 is a diagrammatical view of the wiring arrangement.

Referring more particularly to the drawing, the improved apparatus of our invention is shown incorporated with a conventional mechanism for coiling strip metal which consists generally of a base or frame 2 having a cylindrical metallic coiling block 3 rotatably mounted thereon. The block 3 is adapted to coil continuous strip metal as it is delivered thereto and is adapted to be rotated by any suitable means (not shown). There is arranged forwardly of the base or frame 2 and the coiling block 3, a cold rolling mill, and there is shown in the present instance for the purpose of illustration only the work rolls 4 thereof.

According to the present invention, there is disposed in a laterally extending groove or slot

5 arranged in the periphery of the cylindrical block 3, a metallic insert contacting member 6 having a projecting portion or segment 7 arranged therewith preferably on the inner end thereof. The insert member 6 extends substantially through the width of the block 3 preferably flush with the outer face thereof, and is insulated therefrom by means of an insulating material 8 which is preferably made of fiber, rubber or any other suitable material and which is positioned between the insert member and the walls of the groove 5 in the block 3.

There is suitably arranged preferably in the vicinity of the coiling mechanism, an electrically controlled recording instrument 9. This instrument may be any of the known conventional types, but it is preferable that an Esterline-Angus graphic instrument be provided. Such an instrument consists generally of a rotatable cylinder which is adapted to hold a paper chart and which is driven at a constant speed by a clock mechanism. There is provided a pen which rests on the chart and which makes a continuous straight line on the same as the cylinder revolves, as long as the pen is not moved. The pen is controlled by electromagnets and when the same are energized, the pen is caused to be moved so as to make a mark on the chart substantially perpendicular to the straight continuous line, and it is returned to its normal position usually by means of a spring. Therefore, each electric impulse which energizes the electromagnets will be recorded on the chart of the instrument. The instrument, of course, is suitably connected to a suitable source of power (not shown) to operate the same.

One side of the instrument is connected to the base or frame 2 of the coiling mechanism by means of the line 10 and the other side of the recording instrument is connected preferably to a contact finger 12 by means of line 13. The contact finger 12 is preferably mounted on an insulating block 14 which is suitably arranged preferably on the side of the frame 2 directly opposite the projecting portion or segment 7 carried by the insert member 6.

The improved apparatus of my invention functions in the following manner. The continuous strip of metal S is fed from the pay-off reel through and between the cold working rolls 4 and delivered to the coiling block 3. At the start of the coiling operation of any particular strip, the same is directed around the cylindrical coiling block 3 so as to make the first or inner convolution of the coil. It will thus be seen that this first convolution of the metallic strip contacts both the insert member 6 and the block 3 thereby completing one portion of an electric circuit therethrough. That is to say, an electric circuit

is completed through the insert member 6, the first convolution of the strip S, the block 3, the frame 2 and the line 10, to the recording instrument 9. After the first convolution of the strip has been disposed around the block 3, the projecting portion 7 of the insert member 6 strikes or contacts the contact finger 12 upon each revolution of the block. Thus, it will be seen that when the projecting portion 7 strikes the contact finger 12, the other portion of the electric circuit is completed, namely through the contact finger 12 and the line 13, to the recording instrument 9, thereby energizing the electric magnets of the instrument which in turn move the pen once each revolution of the block. Thereafter, the time for completely coiling the strip of metal on the block 3 can be readily ascertained upon inspection of the chart of the recording instrument. After the coiling of the strip has been completed, the coiled strip is removed from the block thereby breaking the circuit between the insert member 6 and the block 3. Therefore, any further rotation of the block 3 will not be recorded by the recording instrument as there is then not a complete electric circuit.

The improved apparatus of our invention has been shown incorporated with coiling mechanism for coiling strip metal as it is delivered from a cold rolling mill, but it will be understood that it may be used in connection with a coiling block for receiving and coiling the metal from any other machine or process during the manufacture of the strip. Also the improved apparatus of our invention may be incorporated with a coiling mechanism for coiling wire, rod, or other continuous length metallic materials.

While we have, in this application, specifically shown and described one embodiment of our invention, it will be understood that this embodiment is merely for the purpose of illustration and description, and that various other forms may be devised within the scope of the invention, as defined in the appended claims.

We claim:

1. In combination with a rotatable block for coiling continuous strip metal, means for delivering the strip to be coiled to said block, an electric circuit including the coiled portion of the strip itself when coiled around said block, means arranged on the periphery of said block which the first convolution of the strip is adapted to contact when coiled around the same, and means arranged with said last mentioned means for completing the circuit through the coiled portion of strip and said last mentioned means at least once each revolution of said block.

2. In combination with a rotatable metallic block for coiling continuous strip metal, means for delivering the strip to be coiled to said block, an electric circuit including the coiled portion of the strip itself when coiled around said block, a metallic insert member arranged on the periphery of said block which the first convolution of the strip is adapted to contact when coiled around the same, means for insulating said metallic insert member from the remainder of said block, and means carried by said insert member for completing the circuit through the coiled portion of strip together with said insert member and said rotatable metallic block at least once each revolution of the same.

3. In combination with a rotatable metallic block for coiling continuous strip metal, means for delivering the strip to be coiled to said block, an electric circuit including the coiled portion of the strip itself when coiled around said block, a metallic insert member arranged on the periphery of said block which the first convolution of the strip is adapted to contact when coiled around the same, means for insulating said metallic insert member from the remainder of said block, and means arranged opposite said block which said insert member is adapted to contact at least once each revolution of said block so as to complete the circuit through the coiled portion of said strip together with said insert member and said metallic block.

4. In combination with a rotatable metallic block for coiling continuous strip metal, means for delivering the strip to be coiled to said block, an electric circuit including the coiled portion of the strip itself when coiled around said block, a metallic insert member arranged on the periphery of said block which the first convolution of the strip is adapted to contact when coiled around the same, means for insulating said metallic insert member from the remainder of said block, a contact member arranged opposite said block, and means carried by said insert member which is adapted to strike said contact member upon each revolution of said block so as to complete the circuit through the coiled portion of said strip together with said insert member and said metallic block.

5. Apparatus for coiling continuous strip metallic material including a rotatable block for coiling the material, an electric circuit with said rotatable block arranged therein, means carried by said rotatable block which the coiled portion of the strip is adapted to contact when coiled on said block, means for insulating said last-mentioned means from the remaining portion of said block, said electric circuit including the coiled portion of the strip when coiled around said block, and means which said first-mentioned means is adapted to contact at least once each revolution of said block so that the circuit is closed through said rotatable block, the first-mentioned means, and the coiled portion of the strip on said rotatable block when the first-mentioned means contacts said contacting means.

6. Apparatus for coiling continuous strip metallic material including a rotatable block for coiling the material, an electric circuit with said rotatable block arranged therein, a metallic insert member arranged on the periphery of said block which the coiled portion of the strip is adapted to contact when coiled on said block, means for insulating said insert member from the remaining portion of the block, said electric circuit including the coiled portion of the strip when coiled around said block, and means which said insert member is adapted to contact at least once each revolution of said block so that the circuit is closed through said rotatable block, the insert member carried thereby, and the coiled portion of the strip on said rotatable block when the insert member contacts said contacting means.

FRANK MARQUART.
WILLIAM H. STIVASON.
